UNITED STATES PATENT OFFICE

EDGAR A. WANGERSHEIM, OF CHICAGO, ILLINOIS

DESIGN FOR A LIGHTING FIXTURE

Application filed February 16, 1932. Serial No. 42,885. Term of patent 3½ years.

To all whom it may concern:

Be it known that I, EDGAR A. WANGERSHEIM, a citizen of the United States, residing at Chicago, in the county of Cook and State of Illinois, have invented a new, original, and ornamental Design for a Lighting Fixture, of which the following is a specification, reference being had to the accompanying drawing, forming part thereof.

Fig. 1 is a front elevation of a lighting fixture, showing my new design.

Fig. 2 is a side elevation of the same.

I claim:

The ornamental design for a lighting fixture, as shown.

EDGAR A. WANGERSHEIM.
